ROBERT A. FORESMAN AND CHARLES F. MILLER, OF MOORE, PENNSYLVANIA, AS-
SIGNORS TO WESTINGHOUSE ELECTRIC AND MANUFACTURING COMPANY, A COR-
PORATION OF PENNSYLVANIA.

STOKER.

Application filed July 5, 1922. Serial No. 573,018.

This invention relates to mechanical underfeed stokers and has for an object to provide a fuel distributing and agitating mechanism for stokers of the character designated which shall effect an even distribution, an active agitation and a positive feeding movement of the fuel throughout the entire fuel bed with greater uniformity, effectiveness and economy in power consumption than is at present attained in this type of stoker.

These and other objects are obtained by means of apparatus embodying the features of this invention herein described and illustrated in the accompanying drawings in which

Fig. 1 is a view, partially in longitudinal section, through a retort and partially in longitudinal section through a twyer bank of a multiple retort underfeed stoker, substantially as indicated by the line I—I of Fig. 2; Fig. 2 is a view in transverse section of the stoker taken at the line II—II of Fig. 1; Fig. 3 is a plan view of the movable grid; Fig. 4 is a view in longitudinal section of the grid illustrated in Fig. 3; Fig. 5 is a fragmentary view showing the mounting of a twyer block upon the grid; Fig. 6 is a view partially in longitudinal section through a retort and partially in section through a twyer bank of another type of stoker to which this invention may be applied; and Fig. 7 is a longitudinal section through the central retort of the stoker illustrated in Fig. 6, parts being broken away to show operating mechanism.

Referring to the drawings, in Figs. 1 and 2 is shown a multiple retort stoker having retorts 11 and twyer sections 12. A hopper 13 arranged at the forward end of the furnace supplies fuel to the ram boxes 14, whence it is delivered into the retorts by the reciprocating rams 15. As is the common practice, the rams are reciprocated by means of a power shaft 16, cranks 17 and connecting rods 18.

The alternate retorts and twyer sections may be constructed in any suitable manner. As shown, twyer boxes 20 having side walls 21 are disposed in spaced relation. Bottom plates 22 are supported upon lugs 23 projecting from the retort sides 21. The twyers are carried upon the open upper sides

of the twyer boxes 20 and are so disposed that a reciprocation of the twyer bank with relation to the retort sides may be effected. 55

As illustrated in Figs. 1 to 5, a grid or apertured plate 25, of a size to substantially cover the open top of the twyer box 20, is provided with a centrally depending rib 26 and a bifurcated yoke 27. Through the lower ends of the yoke pass rods 28 which extend through the front of the stoker and are associated with the driving mechanism of the stoker in any suitable manner.

The grid 25 is provided with lugs 31 for mounting the twyer blocks 32 in proper spaced relation thereon, the upper twyer block being secured to the grid 25 by means of a bolt 33 and serving to lock the twyer blocks of the entire twyer bank in position 70 on the grid 25. An overhanging block 34 secured to the air box 35 serves to prevent fuel from jamming between the upper end of the twyer bank and the air box.

For the purpose of securing a reciprocation of the grid 25 and the twyer blocks carried thereby, stops 40 are secured to the rods 28 at a position to move the grid to its uppermost position at the end of the outer stroke of rods 28. Stops 41, disposed forward of the yokes 27, are preferably concentric tubes surrounding the rods 28 and secured thereto by threaded connections 42 arranged to be readily accessible from without the furnace, and are adapted to permit an 85 adjustment of the reciprocation of the grid from no movement to its maximum movement. 75

An auxiliary ram 45 is provided in each retort. A drive connection 46 is secured to the ram 45 by means of bolts 47 and extends through a slot in the bottom plate 22. The connection 46 has U-shaped extending arms 48 which at their extremities loosely embrace the rods 28. Stop members 49 on the rods 28 engage the arms 48 to cause a forward and upward movement of the ram 45, and adjustable stops 50 on the rods 28 are disposed to effect any desired reciprocatory movement of the rams. 95

At the rear of the moving twyer bank may be stationary twyers 55, dead plates 56, extension grates 57 and dump grates 58, and at the forward end of the retorts, fuel de-

reflectors 59, all of conventional form and requiring no detailed description in the present specification.

The operation of the apparatus above described is as follows: The driving mechanism of the stoker causes a reciprocation of the rams 15 to feed fuel into the retorts 11. The fuel is directed by the deflector plates 59 upwardly so as to form a fuel bed of considerable thickness over the entire stoker. The rods 28 connected to the driving mechanism are also given a reciprocatory movement and this causes the grids 25 and the twyer blocks 32 carried thereby, as well as the auxiliary rams in the retorts 11, to reciprocate with respect to the retorts. The extent of reciprocation of the grids and auxiliary rams may be varied to produce any desired relative movement of these elements by adjustment of the stops 41 and 50. It results that for any grade of fuel, the proper agitation and rate of progression over the grate may be attained.

In Figs. 6 and 7, this invention is shown as applied to a central retort stoker having lateral retorts of the type described in the copending application of R. B. Mildon, Serial No. 420,015, and assigned to Westinghouse Electric and Manufacturing Company. This stoker comprises a central retort 70 and lateral grates consisting of alternately arranged retorts 71 and twyer sections 72. As shown, a twyer section includes a twyer box 73, a grid 74 mounted thereon and carrying twyer blocks 75. A retort is formed between the adjacent twyer boxes and includes a deflector 77, a bottom plate 78, supported upon side walls 79 of the twyer boxes 73, and an auxiliary ram 80, in a manner similar in all essential details to that described in relation to the apparatus illustrated in Figs. 1 to 4.

In the construction as shown in Fig. 6 the grid 74 and twyer sections 72 are slightly modified in order to better adapt them for use with the type of stoker shown. In accordance with this modification the grid 74 has a depending lip 81 at its end nearest the dump grate arranged to slide over the upper side of a supporting I beam 82 and the side of the dump grate 86. The twyer sections 72 are arranged to span the grid 74 as in the previously described modification, but are held in place with respect to each other by means of depending lugs 83 each fitting into a recess 84 of the next succeeding twyer section. The twyer section 72 nearest the central retort 70 is held in place on the grid by means of a bolt 85 as in the previously described modification.

A main ram 91 operates to feed fuel from the hopper 92 into the central retort 70 and the fuel is distributed along the retort 70 by means of pushers 93 operatively connected to the main ram by rod 94. Two oscillating rods 96 extend from the front to the rear of the stoker one on each side of the central retort 70, and are provided with crank arms 97 disposed centrally beneath each retort and twyer box. The grids 74 and the auxiliary rams 79 are provided with depending lugs 98 and 99, respectively, which are pivotally secured to the ends of the crank arms 97 by means of links 100.

The operation of the apparatus illustrated in Figs. 5 and 6 is not essentially different from that above described with respect to Figs. 1 to 4. Fuel is fed into the central retort by ram 91 and distributed along the retort and over the sides thereof by means of the pushers 93. The fuel overflowing from the main retort is agitated and moved toward the side walls of the furnace by means of the reciprocating twyer blocks and auxiliary rams. There results a continuous agitation and progressive movement of the fuel over the entire stoker from the time the fuel enters the central retort until it is discharged upon the side dump grates.

The operation of the apparatus illustrated in Figs. 5 and 6 is not essentially different from that above described with respect to Figs. 1 to 4. Fuel is fed into the central retort by ram 91 and distributed along the retort and over the sides thereof by means of the pushers 93. The fuel overflowing from the main retort is agitated and moved toward the side walls of the furnace by means of the reciprocating twyer blocks and auxiliary rams. There results a continuous agitation and progressive movement of the fuel over the entire stoker from the time the fuel enters the central retort until it is discharged upon the side dump grates.

While we have shown our invention in but two forms, it will be obvious to those skilled in the art that it is not so limited, but is susceptible of various other changes and modifications without departing from the spirit thereof, and we desire, therefore, that only such limitations shall be placed thereupon as are imposed by the prior art or as are specifically set forth in the appended claims.

What we claim is:

1. In an underfeed stoker, spaced retorts, twyer blocks each spanning the space between adjacent retorts, and means for reciprocating the twyer blocks between any two retorts in unison with relation to the retorts.

2. In an underfeed stoker, spaced retorts having side walls, twyer blocks each spanning the space between adjacent retorts and supported by the side walls, and means for reciprocating the twyer blocks between any two retorts in unison with relation to the retort side walls.

3. In an underfeed stoker, two spaced retorts, an auxiliary ram in each retort, twyer blocks each spanning the space between the retorts, and means for reciprocating the auxiliary rams and twyer blocks with relation to the retorts.

4. In an underfeed stoker, having alternately disposed retorts and twyer boxes, a bank of twyer blocks supported by each twyer box, each block extending from side to side of the twyer box, and actuating means for reciprocating each bank of twyer blocks with respect to the twyer box with which it is associated.

5. In an underfeed stoker having alternately disposed retorts and twyer boxes, a bank of twyer blocks supported by each

5 twyer box, each block extending from side to side of the twyer box, an auxiliary ram in each retort, and actuating means for reciprocating each blank of twyer blocks and each ram with respect to the twyer box.

6. In an underfeed stoker having alternately disposed retorts and twyer boxes, an apertured plate covering each of said twyer boxes, a bank of twyer blocks carried by each of said plates, each block extending from side to side of the twyer box, and means for reciprocating the plates and associated twyer blocks with respect to the twyer boxes.

15 7. In an underfeed stoker, spaced twyer boxes having side walls, twyer blocks carried by the side walls of each twyer box and extending from side to side thereof, and means for reciprocating the twyer blocks with respect to said side walls.

8. In an underfeed stoker, spaced twyer boxes having side walls, retorts between adjacent twyer boxes, the side walls of the twyer boxes also constituting the side walls of retorts, a bottom plate for the retort carried by said side walls, an auxiliary ram in each retort, twyer blocks carried by the side walls of each twyer box and extending from side to side thereof, and means for reciprocating the auxiliary rams and twyer blocks with relation to said side walls.

In testimony whereof, I have hereunto subscribed my name this 27th day of June, 1922.

ROBERT A. FORESMAN. 35

In testimony whereof, I have hereunto subscribed my name this 20th day of June 1922.

CHARLES F. MILLER.

CERTIFICATE OF CORRECTION.

Patent No. 1,611,901.

Granted December 28, 1926, to

ROBERT A. FORESMAN ET AL.

It is hereby certified that error appears in the printed specification of the above numbered patent requiring correction as follows: Page 3, line 4, claim 5, for the word "blank" read "bank"; and that the said Letters Patent should be read with this correction therein that the same may conform to the record of the case in the Patent Office.

Signed and sealed this 5th day of April, A. D. 1927.

Seal.

M. J. Moore,
Acting Commissioner of Patents.
